UNITED STATES PATENT OFFICE.

PERLEY R. PRESCOTT, OF WEST BERLIN, MASSACHUSETTS.

SPEED-CONTROLLER FOR STEAM-PUMPS.

1,023,171.

Specification of Letters Patent.

Patented Apr. 16, 1912.

Application filed May 13, 1910, Serial No. 561,088. Renewed September 8, 1911. Serial No. 648,400.

To all whom it may concern:

Be it known that I, PERLEY R. PRESCOTT, a citizen of the United States, residing at West Berlin, in the county of Worcester and State of Massachusetts, have invented new and useful Improvements in Speed-Controllers for Steam-Pumps, of which the following is a specification.

My invention relates to speed controllers and more particularly to speed controllers for reciprocating steam pumps. Heretofore it has been customary to control this type of pump by hand regulation of the steam supply valve, or "throttle" so called. 15 Or in some cases, by causing the crosshead which operates the steam valve, to actuate a governor at the end of normal stroke. Both of these methods are faulty for the following reason. With hand operation the 20 pump needs constant attention of engineer or attendant, as any change in steam supply pressure, or any change in "head" or working pressure causes a corresponding change in speed. If pump should lose 25 "suction," it is sure to "race" or "run away," which may cause great damage.

In the drawings:—Figure 1 is a side elevation of an ordinary reciprocating steam pump with my invention shown applied thereto and with the parts in section. Fig. 30 2 is a sectional view taken on the line 2—2 of Fig. 1. Fig. 3 is a detail elevation of the driven shaft with the ratchet drums thereon, and Fig. 4 is a section taken on the line 35 4—4 of Fig. 3.

In the case of devices which operate at normal end of stroke, it is well known to engineers, that direct acting pumps do not always travel, same length of stroke, and 40 with large pumps the manipulation of "cushion valves" will change length of stroke several inches. If pump becomes steam or air bound it will "short stroke" that is operate with short strokes in center 45 of its travel. It is obvious from the foregoing, that either of the described methods are insufficient for the purpose.

It is the object of this invention to avoid 50 and obviate all such difficulties and to cause direct acting pumps to operate at desired piston speed, under any and all conditions, by continuously governing the admission of steam, or other fluid pressure, to valve chest, irrespective of the length of piston 55 stroke thereof.

Referring more particularly to the draw-

ing, 1 is the steam cylinder and 2 the valve chest mounted thereon.

3 represents the pump cylinder and 4, the piston rod which connects the piston head 60 in the cylinder 1 and the piston head in the cylinder 3. The cylinders 1 and 3 are braced apart as is usual by a frame-work consisting of four bars 5 which are arranged at each corner of the cylinder casings and 65 form with the piston a quincuncial arrangement. The ordinary cross head 6 is secured to the piston 4 in a manner adapted to engage the tappets 7 on the valve rod 8. Extending laterally from the underneath side 70 of the cross head is a double rack frame 9 having the racks 10 and 11 connected thereto in such a manner as to engage the spaced gears 12 and 13. These gears are mounted upon suitable drums 14 and 15 which are 75 keyed upon a transverse shaft 16 mounted in bearings 17 supported upon the frame rods 5. The gears 12 and 13 have seated in suitable recesses formed in their bodies, spring pressed pawls 18 which are adapted 80 to engage notches 19 formed in the periphery of the drums 14 and 15 in such a manner that one gear will rotate in one direction and the pawl will engage the notches to rotate the shaft, while when operated in 85 the opposite direction the pawl will slide idly over the notches and have no effect upon said shaft. It will be noticed from an inspection of Fig. 2 that the racks 10 and 11 90 are diagonally offset so that they properly engage their respective separated gears and that in the left-hand movement of the piston rod 4, the gear 13 is rotated in a left-hand direction and the gear 12 is rotated in a right-hand direction while in a right-hand movement of the piston 4, the gear 12 95 is rotated in a left-hand direction, and the gear 13 rotated in a right-hand direction.

For sake of convenience I have shown the notches in the drums so arranged as to engage the pawls and rotate the shaft by the action of the pawls 18 in the gear 12 when said gear is operated by a left-hand movement of the piston 4 and the pawls in the gear 13 to operate the gear when the piston 4 100 is moved in a right-hand direction. It will thus be seen that the shaft 16 is continuously rotated.

In order to make the rotation of the shaft 16 more even, I provide a fly wheel 20 which 110 is secured on its right-hand end, and adjacent the fly wheel is mounted a pulley 21

which connects with a pulley 22 on the counter governor shaft 23 by a belt 24. The counter shaft 23 is provided with a bevel gear on its outer end which engages the bevel gear 24' of the governor balls 25. The governor balls as usual are connected by a valve stem 26 to a valve 27 which controls the admission of steam through an inlet pipe 28 to the steam chest 2.

10 From the foregoing, the construction and operation of the invention it is believed will be clearly understood without further description.

Having thus described the invention,
15 what is claimed is—

1. In a device of the class described, the combination with a steam pump piston, of a governor, a shaft belted to said governor, a plurality of oppositely acting gears 20 mounted on said shaft, means controlled by the governor for admitting steam to the valve chest of said steam pump, a valve in the valve chest for controlling fluid pressure to the pump piston, a valve rod, a pair 25 of collars adjustably secured to the valve rod, a cross head carried by the piston and adapted to alternately engage said collars for controlling the throw of the valve to both directions, and an arm carried by the 30 cross head and having a pair of diagonally offset integrally connected rack bars arranged in engagement with the upper and under sides of the respective gears to alternately rotate the same in opposite directions to continuously rotate said shaft in 35 one direction.

2. In a device of the class described, the combination with a steam pump, of a gov-

ernor, a shaft connected with the governor for operating it, a plurality of oppositely acting gears mounted on said shaft, means controlled by the governor for admitting fluid pressure to the valve chest of the steam pump, and an arm carried by the crosshead of said steam pump and having a pair of 45 diagonally offset rigidly connected rack bars arranged in engagement with the upper and lower sides of the respective gears to alternately rotate the same in opposite directions to continuously rotate said shaft in 50 one direction.

3. In a direct acting reciprocating pump, the combination with the cylinder and piston, and a governor for controlling the admission of fluid pressure to the valve chest 55 of the pump, of an arm reciprocating with the piston and having an upper and lower rack thereon out of vertical alinement with each other and rigidly connected, a shaft, a pair of gears rotatably mounted on said 60 shaft, one meshing with one of said racks and the other with the other in all positions thereof, a pair of oppositely acting ratchet devices connecting said gears with the shaft, whereby the variable reciprocation of said 65 rack will rotate said shaft constantly and uniformly in one direction, and means for connecting said shaft with the governor to operate the governor constantly in accordance with the rotation of said shaft. 70

In testimony whereof I affix my signature in presence of two witnesses.

PERLEY R. PRESCOTT.
